CAP FEEDING AND APPLYING APPARATUS

Henry H. Franz, Baltimore, Md., assignor to The Creamery Package Mfg. Company, Chicago, Ill.

Application October 29, 1945, Serial No. 625,254

4 Claims. (Cl. 226—88.1)

1

The invention relates to improvements in devices for closing portable receptacles and especially that class which both feeds and applies caps to containers such as milk bottles.

Most devices of this type, commonly called capping heads, consist of a cap magazine, a pressing station wherein a plunger presses a cap onto a bottle, a traverse slot through which the caps are successively passed from the magazine to the pressing station under the action of an injector plate, and means to reciprocate the injector plate in harmony with the presentation of the bottles to the pressing station.

One of the objects of the present invention is to provide quick and ready means of disassembly of the parts for cleaning.

It is a primary specification of all dairy machinery that all parts contacting, or approaching contact with the product, be readily detachable for cleaning in such a manner that all surfaces be easily and quickly reached with a brush. In prior designs of capping heads, however, the various connections holding the parts together have been made by means of machine screws, press fitted pins, and the like, requiring tools and tedious mechanical work to effect their detachment. The present invention incorporates novel means of assembly in that the interiorly-placed parts are engaged in open-ended or hooked relationship, and the exterior members are retained by a relatively few quick-acting hand-released latches, so that when the latter are uncoupled, the remaining parts are progressively presented for unrestricted detachment.

Another object is to provide a head of greater operating convenience.

In prior designs, the cap platform which forms part of the cap traverse slot, through which the cap passes from the magazine to the pressing station, is bolted to the frame member which forms the other part of the said traverse slot. This precludes ready removal of any of the caps which occasionally become jammed in the traverse slot, the operator having resort to probing for it with some pick-like instrument. In the present invention, the cap platform is readily detached by merely uncoupling a hooked and latched connection, thereby fully opening the traverse slot for ready removal of the jammed cap.

Further, by slanting the cap magazine outwardly, the cap tube in which the caps are normally shipped, and which is normally inserted into the magazine by the operator while the machine is in motion, is brought into a more ac-

2

cessible and convenient position for the operator.

A further object is to provide a capping head of simple construction and dependable operating character.

5 The aforesaid detachable platform obviates any need for the collapsible pins usually provided within the traverse slot for the facilitation of the removal of jammed caps. This, and the fact that the magazine is slanted upwardly and outwardly, 10 allows the lower end of the cap magazine to be placed in closest proximity to the pressing station and shortens appreciably the stroke of the injector plate. As the cap feeding action is derived from the conversion of the vertical displacement of the magazine body into lateral motion of the injector plate, it follows that a shorter stroke of the injector plate for a given displacement of the magazine body results in a greater effect of the weight of the head in causing the 15 injector plate to feed the cap. As a result of this favorable weight stroke relationship, a lesser load may be imposed on the bottle to feed the caps.

Still other objects and advantages of the invention will be apparent from the following description, taken with the accompanying drawings wherein:

Figure 1 is a top plan view;

Figure 2 is a front elevation;

Figure 3 is a sectional elevation with the head shown in readiness to cap an approaching bottle; and

Figure 4 is a sectional elevation of the head in the act of applying a cap to a bottle.

Referring to the drawings 10 represents a support having spaced side walls 11, 11, and a cross member 12 spanning the space between the walls and connected thereto at their upper ends.

40 A cylindrical plunger 14, in cross section, is provided with a stem 15 which has a sliding fit through the cross member 12 and is held in position by a latch member or key 16. A collar 17 is fixed to the stem 15 and interposed between the collar and cross member 12 is a coil spring 18 for urging the plunger 14 downwardly from the cross member.

45 A platform 20 is provided on its upper surface at one end thereof with a headed stud 21 and at its opposite end with a slot 22. Mounted on the platform is a body portion 24 having a slotted end 25 which surrounds the stud 21 and which body 24 is held in position by the head of said stud 21.

The body 24 is provided with a vertical cylinder 27, the bore of which extends through the body 24, and is adapted to receive the plunger head 14. 50 The body 24 is provided with a slot 28 at the end

3

opposite to the slot 25, which registers with the slot 22 in the platform 20. A bolt 29 is received in the slots 22 and 28 of the platform and body 24, respectively. The head 30 of the bolt 29 engaging the upper surface of the body 24, and a nut 31 on the bolt engaging the lower surface of the platform 20 for securing the body to the platform.

The platform 20 is provided with an opening 32 therethrough which registers with the bore of the cylinder 27, and the lower surface of the platform around the opening 32 has a tapered cavity 34 terminating inwardly in a downwardly facing shoulder 35. The lower face of the body 24 and upper surface of the platform 20 are recessed to provide a transverse slot 36, which at the end where it registers with the opening 32 of the platform and bore of the cylinder 27 forms the pressing station 37 for the cap in applying it to a bottle.

Formed on the body 24 is a cap magazine 38 which has the bore thereof disposed at a tangent to the platform 20 so that the caps will be delivered to the slot 36 without jamming. Located in the slot 36 and extending transversely of the body and platform is an injector plate 40, for feeding the caps from the magazine 38 to the pressing station. The injector plate is provided with two upwardly extending flanges 41, 41 which engage the sides 43 of the body 24 in guiding the injector in its movement in the slot 36.

The cylinder 27 is provided on opposite walls with lugs or guides 45, 45 received in vertical grooves 46 formed in the sides 11 of the support 10 to allow for reciprocating movement of the cylinder within the support and relative to the plunger 14, but prevent any rotary movement of the cylinder and body 24 with respect to the plunger. A booster spring 48 is interposed between the upper end of the cylinder 27 and the collar 17 for maintaining the cylinder, body and platform disposed with respect to the collar 17 and the operating end of plunger 14 to insure the various parts functioning in a proper manner.

Rocker arms 50, 50 are disposed at each side 43 of the body 24, and are pivoted on studs 51, 51 formed on the side walls 43. The arms are provided with holes 52, for the reception of the studs 51, adjacent the upper outer edges thereof, while at the forward portions elongated slots 53 are provided.

Collar 17 is provided with oppositely disposed horizontal holes or openings 55, 55. Links 51, 57 are provided at their ends with laterally extending studs 58, 59. The studs 58 of the link 57 entering the holes 55 of the collar 17, and the studs 59 being received in the slots 53 of the rocker arms 50. Each rocker arm 50 is provided on the lower edge with a slot 61, which is located beneath the hole 52 thereof. These slots 61 engage studs 62, 62 on the flanges 41 of the injector plate 40. The links 57 are provided at their upper ends and in alignment with the studs 58 with recesses 64 formed on the outer faces of the links, for the reception of the ends of a spring clip 65 formed somewhat in the shape of a C, for spanning the two links and attaching them to the collar 17. This spring clip retains the links 57 and rocker arms 50 in place, and as the links are disposed exteriorly of the rocker arms they are retained on their pivots 51. It is to be noted that the studs 58, 59 of the links and studs 62 are all in line which eliminates any side torque and obtaining a direct thrust or pull on the pins and their connecting parts during the movement

4

of the rocker arms. By having the pins or studs in line, and on same side of links there will be no twisting or side torque of the studs in their bearings and thereby eliminating frictional resistance.

The oscillating movement imparted to the rocker arms 50 is arrested by stops or lugs 66 on the sides of the cylinder 27 by the forward edge 67 of the rocker arms contacting the stops, Figure 3, and this arrests the injector plate 40 in delivering a cap to the pressing station 37.

It will be appreciated that the links 57 may be detached from the collar 17 upon removal of the spring clip 65, and thereupon the links can be disengaged from the rocker arms 50, upon withdrawing the studs 59 from the slots 53. The rocker arms 50 can now be removed from their studs 51 on the body, and removed from the studs 62 on the injector plate 40 through the slots 61 therein. The platform 20 may now, if it has not been removed before, be disconnected from the body 24 by removing the bolt 29 and nut 31, and then sliding the platform with respect to the body to remove the stud 21 from the slot 25 of the body. This releases the injector plate, and all of the parts are disassembled. The plunger 14 may be detached from the support by removing the key 16.

The body 24, with the attached studs 45, 51 and 66, the rocker arms 50, the injector plate 40 with the attached studs 62, the cap platform 20 with the attached stud 21, the spherical headed screw 29 and the nut 31 comprise a cap feeding assembly which acts as a whole in reciprocating vertically on the cap plunger 14 and is supported in rest position, as in Figure 3, by the engagement of the upper walls of the slots 53 with the studs 59 of the connecting links 57. In this position the cap plunger 14 is in relatively retracted position from the cap in the pressing station, the rocker arms have their facing edges 67 abutted against the studs 66, and the injector plate 40 is in its innermost position with one edge adjacent the cap in the pressing station. The latch member 16 is seated on the upper face of the fixed support 12.

A vertically advancing bottle 68 (Figure 4), is guided by the tapered walls of the cavity 34 until the bottle top is seated against the shoulder 35 with the cap seat in the bottle aligned with the plunger and the pressing station. Further advancement of the bottle results in upward displacement of the aforementioned cap feeding assembly so that the bottle now supports the weight of the assembly and the connecting link studs 59 move from the upper to the lower ends of the arc shaped slots 53 in the rocker arms. At this point the pressing station is approaching the lower end of the cap plunger. Continued advancement of the bottle displaces the cap feeding assembly still further and causes the rocker arms 50 to rock outward on their pivots 51 thereby moving the injector plate 40 out from under the stack of caps, allowing them to come to rest on the lower wall of the traverse slot 36.

Simultaneous with the outward motion of the injector plate, the cap plunger passes through the pressing station, pushing the cap through the hole 32 in the cap platform and into the seat of the bottle.

The seating of the cap in the bottle marks the point at which relative motion between the cap feeding assembly and the cap plunger ceases during the upward motion of the bottle. Further upward motion of the bottle results in equal upward motion of both cap feeding assembly and

cap plunger, the plunger working against the force of the spring 18, the latch member 16 leaving the fixed support a small amount which varies as the heights of the successive bottles, Figure 4.

The cap now being applied, the bottle reverses its direction and starts its departure from the head, allowing the plunger and cap feeding assembly to fall together until the latch member 16 reaches its seat on the fixed support at which time the cap plunger comes to rest and the cap feeding assembly continues downward with the bottle. The lower end of the cap plunger retracts from the cap seat through the hole 32 and through the pressing station after which the connecting link studs 59 having moved back up to contact the upper walls of the elongated slots 53 in the rocker arms.

Further downward motion of the cap feeding assembly with the bottle results in inward motion of the injector plate which carries the bottom cap from the stack of caps in the magazine through the traverse slot to the pressing station.

When the cap reaches the pressing station, the rest position described at the beginning of the operation is reached and the bottle leaves contact with the head.

The above sequence is repeated for every bottle which is advanced to the head.

In case of the presentation of a deformed cap, which generally jams in the traverse slot, it is removed by the following procedure: the operator loosens the nut 31 on the screw 29 just enough to allow detachment of the couple through the aligned slots 22 and 28. The cap platform is then rearwardly detached and the jammed cap is removed, the injector plate being held up against the body, thereby supporting the stack of caps in the magazine.

To disassemble the head for cleaning, the latch member 16 is extracted, allowing the downward detachment of the head from the fixed support and the detachment of the spring 18. The C-shaped member 65 is then removed allowing detachment of the connecting links and the plunger and collar assembly which is made as a single piece not requiring separation. With the detachment of the screw and the nut couple 29 and 31 and the cap platform from the body, the injector plate and operating arms are freed for detachment.

What I claim is:

1. In a bottle capping mechanism, the combination of a support, a plunger mounted thereon having a collar connected thereto, a body member having a cylinder adapted to be slid over the free end of said plunger and to have sliding movement thereon, rocker arms removably pivoted to said body member, an injector plate for delivering caps to said plunger removably pivoted to said rocker arms, and links disposed exteriorly of said rocker arms and having a stud and slot connection therewith, said links having a stud and hole connection with said collar for removably supporting the body member on said plunger and retaining the rocker arms on said body member, and a resilient clip spanning said links for detachably connecting said links to said collar and rocker arms and maintaining said rocker arms on said body member and said links on said collar.

2. In a bottle capping mechanism, the combination of a support, a plunger mounted thereon having a collar connected thereto, a body member having a cylinder adapted to be slid over the

free end of said plunger and to have sliding movement thereon, rocker arms removably pivoted to said body member, an injector plate for delivering caps to said plunger removably pivoted to said rocker arms, and links disposed exteriorly of said rocker arms and having a stud and slot connection therewith, said links having a stud and hole connection with said collar for removably supporting the body member on said plunger and retaining the rocker arms on said body member, and a clip spanning said collar and links for detachably connecting the links together and maintaining said links on said collar and said rocker arms on said body member.

3. In a bottle capping mechanism, the combination of a support, a plunger mounted thereon having a collar connected thereto, said collar having oppositely disposed holes in the sides thereof, a body member and a platform, said platform being provided with a headed stud, said body member having a slot therein for the reception of said headed stud, said body member and said platform having aligned slots, locking means received in said slots for securing the said body member and platform together, an injector plate slideable between said body member and platform and provided with outwardly extending studs, a cylinder and cap magazine formed on said body member, pivot studs disposed on opposite sides of said body member, rocker arms located on opposite sides of said body member and loosely pivoted on said pivot studs, said rocker arms having slots arranged adjacent the upper and lower edges thereof, and the lower slots receiving said injector plate studs, links having studs disposed at each end and along one side thereof, each of said links having a stud thereof received in an upper slot of said rocker arms and having a stud thereof received in a hole of said collar, said links being disposed exteriorly of said rocker arms for retaining the rocker on said body member, and a clip spanning said links and having engagement therewith for connecting said links to said collar and maintaining said studs of said links in said collar and said rocker arms.

4. In a bottle capping mechanism, the combination of a support, a plunger mounted thereon, a collar connected to said plunger, a platform and a body member mounted thereon, means for detachably connecting the body member to the platform, a cylinder for the plunger on said body, an injector plate for delivering caps from the magazine to the plunger, rocker arms pivotally mounted on the body, means for connecting said rocker arms to said injector plate, links detachably pivoted to said rocker arms and said collar, and a clip spanning said links and having the ends thereof engaging said links for detachably connecting said links to said collar.
